CLAIM

The ornamental design for a mobile computing device, substantially as shown and described.

DESCRIPTION

FIG. 1 is a perspective view of a mobile computing device showing the new design;

FIG. 2 is a front elevation view of the mobile computing device of FIG. 1;

FIG. 3 is a rear elevation view of the mobile computing device of FIG. 1;

FIG. 4 is an elevation view from the right side of the mobile computing device of FIG. 1;

FIG. 5 is an elevation view from the left side of the mobile computing device of FIG. 1;

FIG. 6 is a top plan view of the mobile computing device of FIG. 1; and,

FIG. 7 is a bottom plan view of the mobile computing device of FIG. 1.

The broken lines show portions of the mobile computing device which form no part of the claimed design.

1 Claim, 5 Drawing Sheets
